UNITED STATES PATENT OFFICE.

GEORGE R. VESTAL, OF OWENSBORO, KENTUCKY.

PENHOLDER.

Application filed September 28, 1922. Serial No. 591,100.

To all whom it may concern:

Be it known that I, GEORGE R. VESTAL, a citizen of the United States, residing at Owensboro, in the county of Daviess and State of Kentucky, have invented certain new and useful Improvements in Penholders, of which the following is a specification. This invention relates to pen holders and seeks to provide a pen holder, the cost of which will be very little, if any, greater than the ordinary pen holder now in common use and which will be provided with means whereby rolling of the pen about a desk or other flat surface will be prevented. The invention also has for its object the provision of a pen holder which may be placed upon a desk or other writing surface while ink remains upon the pen without liability of the ink being brought into contact with exposed papers or other objects. The stated objects of the invention and other objects which will incidentally appear in the course of the following description are attained in such a device as is illustrated in the accompanying drawings, and the invention resides in certain novel features which will be particularly pointed out in the appended claims.

In the drawings—

Figure 1 is a side elevation of a pen holder constructed in accordance with my invention:

Fig. 2 is a similar view showing the pen holder lying upon a flat surface but supporting the pen out of contact with said surface;

Fig. 3 is an enlarged longitudinal section through the end of the device, and

Fig. 4 is a perspective view showing the fingers which prevent the rolling of the pen holder and illustrating the sleeve which controls said fingers pulled back so as to permit the fingers to act.

The pen holder may be constructed of wood or other material and is of the general formation shown at 1, being the tapered circular shank or handle now generally used. At the forward end of the handle 1, I provide a tenon 2 and secured upon said tenon in any convenient or preferred manner is a bushing or sleeve 3 which projects beyond the tenon and is provided at its outer end with an annular stop flange 4. Within the sleeve or bushing 3 are provided the usual resilient fingers 5 which are adapted to hold the pen 6 within the holder in the usual

manner. Upon the outer surface of the sleeve 3 are mounted fingers 7 which are of resilient metal and extend longitudinally of the sleeve, as clearly shown, the outer ends of said fingers being free while the inner ends thereof are secured to the sleeve by brazing or any other preferred means. It will be readily noted that the inner ends of the sleeve and of the fingers abut the annular shoulder 8 provided upon the handle 1 by the formation of the tenon 2. An outer sleeve 9 is slidably fitted upon the end of the handle and is of such length that its inner end may encircle the handle while its outer end will abut the stop flange 4, as clearly shown in Fig. 3. This operating sleeve 9 may be constructed of rubber, cork, wood, or any other material which will be light and durable and comfortable to the fingers of the user. To prevent excessive wear upon the said sleeve by the resilient fingers, a lining sleeve 10 of metal is fitted within the bore of the said sleeve, as shown clearly in Fig. 3, and the free ends of the fingers 7 bear against this lining. It will also be noted that the lining should be of such diameter that it may readily extend over the end of the handle and the shoulder 8 should be of such width that ample clearance will be provided to prevent the fingers bearing against the lining with excessive force and thereby interfering with the free operation of the parts.

When the pen holder is in use, the outer operating sleeve 9 will be in its forward position shown in Fig. 1 and will compress and house the resilient fingers. When the writing is completed or interrupted and the pen is to be put aside, the sleeve is retracted, as shown in Fig. 2, whereupon the fingers 7 will assume positions projecting from the inner sleeve 3, as clearly shown in Fig. 2 and by dotted lines in Fig. 3, so that if the holder be then placed upon the surface of a desk or writing table, the ends of the fingers will bear upon said surface and will cause tilting of the holder, as shown in Fig. 2, whereby the pen will be held out of contact with the writing surface. The fingers are preferably spaced ninety degrees apart and, therefore, they will be disposed in substantially rectangular relation so that, when the pen holder is put aside, two of the fingers will engage the surface upon which the holder is placed and rotation or rolling of the holder will be thereby prevented. In-

asmuch as the pen will be supported above the writing surface and the pen holder cannot roll around upon the same, contact between the pen with ink thereon and papers or other objects cannot occur. The device is exceedingly simple and can be produced at a very low cost and may be used as freely and as extensively as the ordinary pen holders now employed without causing any additional fatigue to the user.

Having thus described the invention, what is claimed as new is:

- 15 1. A pen holder provided at its forward end with spring fingers adapted to project from the holder and engage a surface upon which the holder may be placed, and a sleeve fitted upon the end of the holder and adapted to house said fingers and maintain them in inoperative position.
- 20 2. A pen holder provided at its forward end with longitudinally extending resilient

fingers secured at their inner ends to the holder and having their free ends adjacent the forward end of the holder to support said end out of contact with the surface 25 upon which the holder may rest.

3. A pen holder comprising a handle, a sleeve secured to the end of the handle and extending longitudinally therefrom and provided at its outer end with a stop flange, 30 means within said sleeve for gripping a pen, an outer sleeve slidably fitted upon the handle and adapted to abut the stop flange on the first-mentioned sleeve, and resilient fingers secured upon the inner sleeve in spaced 35 relation and adapted to be compressed and housed by the outer sleeve in a forward position of the latter and project laterally beyond the same when said sleeve is retracted.

In testimony whereof I affix my signature.

GEORGE R. VESTAL. [L. S.]
